UNITED STATES PATENT OFFICE.

GEORGE S. ATKINS, OF SCRANTON, PENNSYLVANIA

CONVEYER.

Application filed March 24, 1927. Serial No. 178,011.

This invention relates to conveyers and particularly to conveyers which are composed of separable links pivotally connected to each other at their adjacent ends and carrying 5 conveyer elements or members detachably engaged therewith.

One of the objects of the present invention is to provide a conveyer which is made up of links as stated before, but in which the 10 links used are of exactly the same form and character so that the same links may be used in pairs to form the chain, the links being capable of such arrangement that there are two spaced inner links and two spaced outer 15 links.

A further object is to provide means for locking the pivot pin in engaged position to thereby prevent the pivot pin from turning to a position where it will release the links 20 unless the links are slid upon each other to a considerable degree.

Another object is to provide means whereby a conveyer member may be readily engaged with the inner pair of links without the 25 use of bolts or other fastening devices and will be held firmly in position, and in this connection, provide means whereby the conveyer member may be held in engagement with the links, either closely adjacent to the 30 pivot pin or in spaced relation thereto.

A further object is to provide each of these links with a longitudinally extending slot intersected by a transversely extending web, which web is disposed, not at the middle of 35 the link, as is the usual practice, but relatively near one end of the link, the conveying member being so formed as to permit it to be disposed between these webs of the inner links and the pin.

40 A further object of this construction is that the inner links may be disposed reversely, end for end, so that the conveying member may be disposed between the webs of these two links in case the pin has become 45 worn so as to make the conveying element loose.

A still further object is to provide the heads of the links with outwardly projected lugs having faces extending parallel to the 50 slots of the links, these lugs constituting spacing members for the two inner links and pin locking members for the two outer links, one of said lugs also acting as an abutment on the inner link against which the shank of 55 the conveyer member abuts and engages.

Other objects will appear in the course of the following description:—

My invention is illustrated in the accompanying drawings wherein:—

Figure 1 is a side elevation of a portion of 60 the conveyer chain constructed in accordance with my invention.

Figure 2 is a top plan view thereof.

Figure 3 is a longitudinal section on the line 3—3 of Figure 2. 65

Figure 4 is a longitudinal section on the line 4—4 of Figure 1.

Figure 5 is a side elevation showing a different assembly of the links to permit a different positioning of the scraper blade. 70

Figure 6 is a longitudinal section on the line 6—6 of Figure 5.

Figure 7 is a section on the line 7—7 of Figure 5.

Figure 8 is a section on the line 8—8 of Figure 5. 75

Figure 9 is a perspective view of one of the links.

Figure 10 is a perspective view of the conveyer member. 80

Referring to these drawings, it will be seen that the conveyer is formed of a chain composed of a plurality of pairs of links. Each link is absolutely the same as any other link and, therefore, a description of one link 85 will suffice for all. Each link consists of the body portion 10, having rounded ends or heads 11 having the same width as the body portion, and each link is formed with a longitudinally extending slot 12 intersected by 90 a reinforcing cross bar or web 13 which is formed integral with the upper and lower bars which constitute the body of the link. The heads at opposite ends of the link are somewhat thickened, and at the junctions of 95 the heads with the body of the link there are formed shoulders 14. One end of each link is formed with a laterally projecting lug 15 whose inner edge is coincident with the shoulder 14 and the opposite head is also 100 formed with a lug 15 which is precisely the same as the previously referred to lug except that if the first lug 15 is disposed at the top of the link, the opposite lug 15 will be disposed at the bottom of the link. Each of 105 these lugs has a flat inner face 16.

The conveyer chain is formed by assembling the links as shown in Fig. 2. Two of the links are placed together to form the inner links and two more links are disposed ex- 110

teriorly of the first named pair of links to constitute the outer links. The inner links are placed together so that the lugs 15 will hold the inner pair of links in spaced relation, the outer faces of the heads of the links thus being flat. The outer links are assembled so that the lugs 15 project laterally outward. Holding the outer pair of links in engagement with the inner pair is the transversely extending pin 17 which is cylindrical in cross section, this pin being provided with heads 18 at its ends. These heads have a width such that when the pin is turned so as to carry the heads into parallel relation to the slots 12, the links may be withdrawn from their engagement with each other after the links have been shifted longitudinally. Preferably the heads 18 are eccentric with relation to the pin 17. Thus each head projects in one direction somewhat more than it projects in the opposite direction. In actual practice, the edge 19 of the head on the shorter end thereof will initially bear against the flat face of the lug 15 as shown in Figure 1 so that the pin cannot rotate until the link has been shifted longitudinally a sufficient distance to cause the lug 15 to escape the head. In case, however, that wear takes place between these two surfaces so that the pin becomes loose and is not locked securely in place, than the pin may be turned over and the edge 19 of its longer end may be then engaged with the worn lug 15.

Disposed between the inner pair of links is the shank 20 of a conveyer member 21 which may be of any suitable character but is shown as a scraper blade formed integral with the shank 20. The shank 20 carries the laterally projected lugs or thickened portions 22 which have a width such as to fit snugly between the upper and lower bars of the link and are located so that this lug will fit between the reinforcing cross bars of the two links and the pin 17, with the shank 20 abutting against the lug 15 of one of these inner links as shown in Figure 3. Preferably the shank 20 will be extended downward beyond the laterally projecting portion 22 as at 23, this portion 22 also fitting between the links.

In assembling the chain with the conveyer member, the inner links are slid longitudinally upon the outer links and the outer links are laterally separated so that these inner links may be shifted into divergent relation to each other. Then the conveyer member may be shifted longitudinally upon the inner links until it bears against the pin, the inner links are closed together, the outer links forced inward and then shifted longitudinally until the parts are in the position shown in Figure 1.

It will be seen that this construction provides means for positively engaging the conveyer element with the chain elements without any bolts, rivets or any other fastening devices. Furthermore, it will be seen that the conveyer element is held firmly in place with its web 20 or shank abutted against the upper lug 15 at that end so that any strain placed upon this conveyer member 21 is borne by this adjacent lug 15, by the pin 17, and by the engagement of the laterally projecting portions 22 within the spaces defined by the webs 13, the adjacent heads of the links, and the upper and lower body portions of the links. This permits the ready disassembly or removal of these conveyer members when desired. It is particularly pointed out that the inner links are not spaced from each other merely by the shank 20 or portion 22 of the conveyer member, but that the links are spaced apart by the abutting of the lug 15 of one link against the body portion of the next inner link, so that these inner links are held in rigid spaced engagement at opposite ends which would not be the case were the links merely spaced apart by the shank of the conveying element.

There is a further advantage in this construction. If the pin should become worn or the faces of the intersecting reinforcing portions 13 become worn, the conveyer member may be shifted in position as shown in Figure 5, that is, one of the links 10 of the inner pair is reversed end for end so that the reinforcing web 13 of one link is not directly opposite of the reinforcing web 13 of the adjacent link of the pair, but they are disposed in longitudinal spaced relation at such distances apart that the face 22 as it may be called of the conveyer element may be disposed between these two reinforcing webs 13 of the adjacent links and again be held in firm position. Thus, the particular construction of these links provides for two positions of the conveyer member.

The advantages of my construction are as follows: Inasmuch as all of the links are absolutely alike, they may be cast in one mold or otherwise formed without having to form two different sets of links. This aids in the ready assembling of the links as the only requisite is that the links shall be assembled so that the links of each pair are reversely disposed to each other. Otherwise there is no particular care to be taken in the assembly of the parts. The other pair of links, however, are assembled so that the lugs 15 extend inward instead of outward. By placing the reinforcing webs 13 relatively closer to one end of the link than the other end, not only is the conveyer member capable of being changed in position when the parts are worn as previously referred to, thus rendering it unnecessary to discard the worn links or leave the conveying member loose therein, but the necessary length of the base of the conveying member 21 is much reduced, thus materially reducing the weight. While the weight of the chain formed by the pairs of inner and outer links is increased, the weight of the conveying member 21 is reduced, thus materially reducing the weight of the chain.

outer links is increased over chains having alternate single and double links, the weights of the conveyer members are decreased and thus the total weight of the conveyer, (including the conveyer chain) is very considerably reduced and the cost of the conveyer is correspondingly reduced.

The conveyer members 21 are firmly held in position between the reinforcing webs 13 and the pin, and with the link of each conveyer member abutting against the face 14 of the upper rearward lug 15 of each pair of inner links. Thus, the conveyer member is held firmly against play. The abutment of the lugs 15 against the opposed flat faces of the adjacent link spaces the links from each other and inasmuch as the outer faces of the lugs 15 are relatively long and flat any wear is distributed. In order to detach the links from each other, they do not have to be collapsed and then angled as do chains of that type having single links alternating with double links. My chain is connected and disconnected with the connecting pairs of links, held in a horizontal position only, or in alignment with each other. No lateral collapsing of the links is necessary and they may be connected or disconnected without the use of any tools whatever. By offsetting the head 18, that is having it project from its axial center in one direction more than in the other direction, the pin may be reversed so as to have a proper contact with the inner faces of the corresponding lugs 15 after the face of the relatively shorter portion of the head and the face of the corresponding lug has become worn. The pin is held against rotation which would turn the heads into parallel relation to the slots of the links by the relatively long contact between the end faces of the heads and the inner faces of the lugs 15, so that one pair of links would have to move quite a considerable distance rearward in order to disengage the heads from the lugs 15 and permit accidental rotation of the heads into a disconnected position. This would not be the case were an end abutment on a link provided to engage the head of the pin. In that case even a slight movement of the head of the pin away from this abutment would tend to permit the rotation of the head to some extent and this would tend to wear the confronting faces so that shortly the pin would be very readily rotated.

The outstanding advantage of my conveyer chain is that where all other conveyer chains on the market known to me use pairs of bolted or riveted conveyer members which are liable to become loose and break from strains, my construction entirely does away with any bolting or riveting and the conveyer member is disposed between and detachably interlocked with two closely adjacent inner links. Thus I eliminate the cost of assembly, renewals and the more or less constant

necessity of tightening up bolts or rivets and do away with the necessity of constant work while these repairs are being made. Furthermore the conveyer member so constructed is much lighter and consequently much cheaper to produce and the cost of bolts and rivets and the weight thereof entirely eliminated. Only one pattern of link is made, thus reducing the cost of dies and only one pattern of pivot pin is used. Only one pattern is necessary for the conveyer member, thus eliminating the necessity of using a right and left pattern therefor.

Attention is called to the fact that the extension 23 on the base 22 provides against lateral strains when a conveyer is carrying its load on one side. Thus, when such strains come in operation instead of the side or lateral strain coming only on the web 20 and against the upper and the two middle link walls, the lower walls of the two links will bear their share of this lateral strain. There is thus much less liability of the middle links becoming outwardly distorted or fractured inasmuch as the strain is evenly distributed in horizontal section.

I claim:—

1. A conveyer composed of like links arranged in pairs to provide alternately an inner and an outer pair of links, each link having a longitudinal slot intersected by a reinforcing web and disposed nearer one end of the slot than the other end and relatively adjacent the first named end of the slot, headed pins connecting said links, and a conveying member having a shank disposed between the inner pair of links and having a base portion projecting laterally into the slots, said laterally projecting portion having a length equal to the distance between the webs and the adjacent pin and disposed in and fitting between said webs and the adjacent pin.

2. A conveyer composed of like links arranged in pairs to provide alternately an inner and an outer pair of links, each link having a longitudinal slot intersected by a reinforcing web, each link having at opposite ends a laterally projecting lug, the lug at one end of the link being disposed in a diagonally opposed position to the lug on the other end of the link, the inner pair of links being disposed with their lugs extending inward, the outer pair of links having their lugs projecting outward, headed pins connecting said links, the heads of the pins engaging the lugs of the outer links and being held from rotation thereby, the heads of the links having a width nearly equal to the width of said slots and a conveying member having a shank disposed between the inner pair of links and having a base portion projecting laterally into the slots and disposed in and fitting between the reinforcing webs and the adjacent pin, said conveyer member

having a shank extending upward from the base portion and fitting the space between the inner pair of links and bearing against the adjacent lug on one of said inner links.

5 3. A conveyer composed of like links arranged in pairs to provide alternately an inner pair and an outer pair of links, each link having a longitudinally extending slot intersected by a reinforcing web, the web 10 being disposed relatively close to one end of the link and nearer to one end of the link than to the other end of the link whereby the inner pair of links may be assembled so as to bring said webs immediately opposite 15 to each other or in offset relation, headed pins engaging the pairs of links with each other and a conveyer member having a shank fitting between the inner pair of links and having a laterally enlarged base portion adapted to 20 fit between both of said reinforcing webs of the pair of links and the adjacent pin or between one of said reinforcing webs and the adjacent web of the opposite link, when said links are disposed with their webs in offset 25 relation.

4. A conveyer including alternate pairs of duplicate single links, each link having a longitudinally extending slot, the slot being intersected by a reinforcing web adjacent 30 one end of the link, the links being arranged in pairs to provide alternately an inner and an outer pair of links, the outside links being formed with outwardly projecting pin-locking lugs, the inside links being formed with 35 inwardly projecting spacing lugs, said lugs being formed upon the walls of the opposing top and bottom heads of the links and extending parallel with the slots, a double headed pin adapted to slidably engage said 40 lugs at opposite sides of alternate pairs of outside links in operative engagement therewith to thereby cause the outside links to rigidly interlock with the pin and the inner links to freely oscillate on the pin, and a conveyer member having a shank disposed between the inner pair of links and interlocked 45 with said links.

5. A conveyer comprising alternate pairs

of duplicate single links, each formed with a longitudinally extending slot intersected 50 by a reinforcing web adjacent one end of the link, the pairs of links being assembled to provide alternately inner pairs and outer pairs of links, the outside links being formed with outwardly projecting pin-locking lugs 55 and the inside links being formed with inwardly projecting spacing lugs, said lugs being formed upon opposite heads of the links and having inner faces extending parallel with said slots, connecting pins, each 60 provided at its opposite ends with rectangular heads adapted to slidably engage the inner faces of the lugs at opposite ends on opposite sides of alternate pairs of outer links to permit free oscillation of the inner links on the 65 pin and to interlock the outer links with opposite heads of said pins, and a conveyer member interlocked in said slots of the inner pair of links between the reinforcing webs 70 thereof and the adjacent pin.

6. A conveyer comprising alternate pairs of single links, the links being duplicates, each link being formed with a longitudinally extending slot intersected by a reinforcing web adjacent one end of the slot, each link 75 at its opposite ends being provided with laterally projecting lugs having inner faces parallel to the link, the lug on one end of each link being diagonally disposed with relation to the lug on the other end of the 80 link, the inner links being assembled reversely to the outer links to permit said lugs to act as spacing lugs, the outer links having their lugs projecting outward, pins connecting said pairs of links, each pin being provided with rectangular heads at opposite ends adapted to slidably engage the inner faces of the lugs, and a detachable conveyer member having a shank extending downward 85 between an inner pair of links, the shank having a laterally projecting base portion interlocked between the reinforcing webs of the inner pair of links, and the upper and lower walls of the slots of said links.

In testimony whereof I affix my signature.
GEORGE S. ATKINS.
